UNITED STATES PATENT OFFICE

2,460,519

WORKING OF HIGH TENSILE SHEET METAL

Lee L. Marchant, Takoma Park, Md., assignor to
Engineering and Research Corporation, River-
dale, Md., a corporation of Maryland

Application May 31, 1945, Serial No. 596,887

1 Claim. (Cl. 219—3)

1

This invention relates to the dimpling, punching, shearing or other working of sheet metal and, more particularly, to the working of sheet metal of such high tensile strength that it tends to rupture or crack when worked cold. While the invention is applicable to any such working of high-tensile sheet metal it will be described herein in connection with the dimpling of such sheet metal.

It has been found that if usual and known dimpling means are utilized to dimple high-tensile sheet metal, such as magnesium or high tensile aluminum sheet, the metal surrounding the dimple will crack and shatter when the pressure applied to the dimpling die is increased sufficiently to cause dimpling to take place. While it is known to reduce tensile strength by heating in order to permit working, such methods and means for effecting this as are presently available are not useful where it is necessary to localize the heating or where rapid operation is necessary or desirable.

The present invention provides a method of, and means for, dimpling high-tensile metal sheet without causing such cracking and rupturing. In the method according to the invention the dimpling die is forced against the sheet with a known available pressure which is insufficient to dimple the sheet while cold and is also insufficient to rupture or crack it. Simultaneously, the sheet is momentarily heated at and closely adjacent the area of contact of the die until the tensile strength of the sheet at such area of contact is decreased to a value at which it is equal to or slightly less than, the pressure applied to the sheet by the dimpling means, at which time the die will dimple the sheet. The heating is performed by the application of electric power to the sheet and in accordance with the invention more than sufficient power to effect the necessary heating is applied, whereby a very rapid increase in temperature at the area of contact is produced, thus localizing the heating and providing a very rapid operation.

In the drawings, in which similar reference numerals refer to like parts,

Fig. 1 is a partly diagrammatic, partly sectional view showing parts of a punching and riveting machine embodying the invention and showing the parts in their respective positions just prior to the dimpling and punching operation, and

Fig. 2 is a view showing the parts illustrated in Fig. 1 after completion of the dimpling and punching operation.

2

The high-tensile sheets with which the invention is particularly useful are those which, when dimpled cold, will crack and shatter about the dimple because of the high tensile strength of the material. Each such material has a so-called "critical range" which is defined, for the purposes of this application, as the temperature, or range temperature, at or below which the tensile strength of the material is such that cracking or shattering will occur when the sheet is dimpled and above which the tensile strength of the material is such that these undesirable effects are not produced. For the purposes of this application, the word "cold" will be understood to mean temperatures below this critical temperature or range.

In the drawings there are disclosed parts of a punching and riveting machine of known type and embodying means for carrying out my invention. The machine parts comprise a dimpling die 2 which is mounted on the lower end of a vertical piston rod 4 which is movable vertically by a piston 6 mounted in a cylinder 3 to which fluid under pressure may be introduced or exhausted through pipes 10, 12 in order to move the dimpling die. Below the dimpling die is mounted an anvil 20 having an opening therethrough in which a punch 22 is mounted for vertical movement. These described parts are conventional and well-known, being disclosed, for example, in my co-pending application Serial No. 585,134. In the operation of these known means, metal sheets 30 are placed on the anvil and the dimpling die is forced downwardly against them in order to simultaneously dimple and punch the sheets.

Means are provided by the invention for momentarily heating the sheets 30 during the application of the dimpling die thereto. Such means comprise an insulating member 40 which surrounds the anvil at the upper end thereof and supports a high-resistance contact member 42 which extends above the upper end of the insulating member and the anvil and is adapted to support the sheets 30. Electric energy is adapted to be supplied to the contact member 42 through a connecting device 44 and to the dimpling die 2 through connection 46.

In accordance with the invention cold sheets 30 of high-tensile sheet metal are laid on the upper end of the contact member 42 and the dimpling die is forced downwardly against the sheets with a force which is insufficient to dimple the sheets while cold and which is preferably approximately sufficient to dimple the sheet at the critical temperature or critical range of tem-

peratures. As this pressure is insufficient to cause dimpling the parts will remain in the positions shown in Fig. 1. Contact between the dimpling die and the sheets will, however, complete the described electric circuit causing current to flow through the dimpling die, sheets and resistance member 42, and causing the sheets to become heated at and adjacent the area of contact of the dimpling die. In accordance with the invention the electric energy provided by this circuit closure is more than sufficient to raise the temperature of the said localized area of the sheets to a value at which dimpling will take place without undesired rupture or shattering. The temperature of the sheets at this localized area will therefore be very rapidly increased and the tensile strength very rapidly decreased. When the tensile strength is decreased by increase in temperature, to a value at which the pressure applied to the dimpling die is sufficient to dimple the sheet the dimpling will occur, after which the immediate removal of the die 2 from the sheets will break the circuit and stop the heating. I have found that the surge of excess electric energy through the localized area of the sheets not only provides very rapid operation but restricts the heating to the area at and closely adjacent the point or area of contact between the dimpling die and the sheets. This permits the sheets to be held in the hand during the dimpling operation, although very high temperatures are produced at the dimpling area.

In the machine disclosed in the drawings, a punching operation is performed simultaneously with the dimpling. This is usual in punching and riveting machines of known types and is well within the spirit and scope of the invention.

While I have described and illustrated one method and means according to my invention, modifications in such method and means may occur to those skilled in the art, all of which may

be made without departing in any way from the spirit and scope of the invention, for the limits of which reference must be had to the appended claim.

5 What is claimed is:

The method of working metal, which metal has such a high tensile strength that it tends to crack and shatter when worked cold, which consists in applying a working tool to the metal with a pressure insufficient to work it in the desired manner while cold but which is sufficient to work it in the desired manner at a temperature of the metal just above the critical temperature thereof, and while maintaining such pressure applying to the metal at the area of contact of the working tool electric energy in amount more than sufficient to cause the metal to be heated to a temperature at which the tensile strength is such that the pressure applied to the tool will cause the desired working.
